UNITED STATES PATENT OFFICE.

LUDWIG SANETRA, OF CHICAGO, ILLINOIS.

DESIGN FOR A PICTURE-FRAME.

49,676.

Specification for Design. Patented Sept. 19, 1916.

Application filed July 24, 1916. Serial No. 111,090. Term of patent 7 years.

To all whom it may concern:

Be it known that I, LUDWIG SANETRA, a subject of the Emperor of Austria-Hungary, residing at Chicago, in the county of Cook and State of Illinois, have invented a new, original, and ornamental Design for a Picture-Frame, of which the following is a specification, reference being had to the accompanying drawing, forming part thereof.

Figure 1 is a front elevation of my design for picture frame, and, Fig. 2 is a top plan view thereof.

I claim:

The ornamental design for a picture frame, as shown.

LUDWIG SANETRA.

Witnesses:

KAVAL NASTUCHACZ,
KISTO PETROFT.
